GARMENT

Verne L. Stephenson, Goshen, Ind., assignor to
Snuggle Rug Company, Goshen, Ind., a corpora-
tion of Indiana

Application November 22, 1933, Serial No. 699,105

4 Claims. (Cl. 2—114)

This invention relates particularly to infants' garments and especially to sleeping garments of the class exemplified by the Bates Patent No. 1,556,747, the Young Patent No. 1,735,521 and the Thexton Patent No. 1,875,525, and including crib covers, sleeping suits and sleeping bags for indoor and outdoor use. In garments of this type it is desired that the neck opening or neck-band be so constructed that it may be adjusted to fit closely around the baby's neck, not simply for the sake of warmth, but in order that the child shall not be able to squirm out of the garment or get its face covered. Difficulty has, however, been experienced in obtaining such close fit without discomfort or danger. The object of the present invention is to overcome this difficulty.

In the accompanying drawing,

Figure 1 is a face view of a sleeping cover embodying the features of my invention.

Fig. 2 is a fragmental view, on a larger scale, showing the construction of the neck-band.

Fig. 3 is a similar view, on a still larger scale.

Fig. 4 is a transverse section through the neck-band on dotted line 4—4 of Fig. 2.

Fig. 5 is a view similar to Fig. 4, but showing a tubular core.

Fig. 6 is a diagrammatic representation of a prior-art neck-band.

While it will be understood that the present invention is applicable to sleeping bags as well as crib covers, I have shown it as embodied in a crib cover 1. As herein shown the crib cover comprises arm-covers or extensions 2, but they may be omitted, if desired.

The front of the garment is formed to provide a longitudinal opening through which the child may be inserted and removed, this opening being closed by means of a slide fastener 3 or by any other desired method. The fastener 3 stops short of the neck opening 4, in order to keep metal parts away from the infant's neck and chin, the intervening distance being closed by a flap 5.

The neck-band, as a whole, is designated A in the drawing. It comprises a tubular portion A' formed of fabric, the ends of which tubular portion may be brought into proximity to each other to extend around the baby's neck. The ends of the portion A' may be adjustably secured together in any preferred manner, as by means of a tape A² attached to one end of the portion A' and carrying a socket fastener A³ adapted to snap over any one of a number of stud fasteners A⁴ arranged in a series adjacent to the other end of the tubular portion A'.

Lying loose within the tubular portion A' is an elongated, cylindrical core A⁵ of soft, flexible material, the core being of approximately the same length as the tubular portion and being approximately one-half inch in diameter. The 60 ends of the tubular portion are closed by means of stitches so as to retain the core in place.

The core A⁵ may be tubular, as shown in Fig. 5,

or non-tubular, as in Fig. 4. It may be of any soft, flexible material, such as soft rubber, felt, 65 a fabric tube filled with cotton or kapok, or any other structure which is sufficiently soft and yielding to be comfortable, but at the same time possessing sufficient bulk, stiffness and stability

as will prevent such folding or kinking as would 70 seriously reduce the effective diameter of the neck-band. This will be better understood by

reference to Fig. 6, which is a diagrammatic representation of a prior-art neck-band x formed of fabric. Assume that a baby has been tucked 75

into a garment having such a neck-band: When the child changes its position the neck-band

may become folded or kinked in the way indicated generally at y in Fig. 6, thus decreasing the effective diameter of the neck-band and produc-

80

ing excessive and even dangerous constriction of the neck. The fold, tuck, kink or shortening y

may happen in various ways; for example, babies being usually plump, a portion of the neck-band

may be caught or squeezed in a fold of the skin 85

of the neck and pulled as the child turns, thus reducing the effective length of the neck-band.

My improved form of neck-band is designed to have sufficient thickness or bulk so that it cannot

be held in a wrinkle of the neck. It should also 90

be sufficiently thick so that it will not "cut" into the neck; when subjected to pressure it should

flatten so as to present enough surface so that it will not make a sharp indentation in the neck.

While softness is important for the sake of com-

95

fort, the core should preferably be sufficiently self-sustaining or stiff so that it will not form a

sharp bend, as such a bend might in some cir-

cumstances cause objectionable reduction in ef-

fective diameter of the neck-band.

100

A non-tubular core of soft, flexible rubber

which will yield readily to such pressures as occur

between the neck and the bedding satisfies very

well all the practical requirements, but the in-

vention is not limited to such a core.

105

In use, the core A⁵ imparts a desirable degree

of stability or shapeliness to the neck-band A

without any objectionable rigidity or hardness.

The core A⁵ flexes to conform to varying degrees

of pressure and various positions of the head and 110

neck as the child changes its position, but the proper diameter, or more properly speaking, the circumference of the neck-band is maintained at all times. It will be seen that the core keeps the 5 tubular portion A' sufficiently distended to its proper length at all times, thus preventing the adventitious formation of folds or tucks in the neck-band which would shorten its effective length. Hence, although the neck-band fits 10 snugly around the child's neck, there is no danger of accidental constriction, nor any uncomfortable hardness or stiffness.

While the drawing shows the tubular portion 15 as wholly free of wrinkles, it will be understood that in practice said portion, being made of fabric, will be more or less loose and will thus contain wrinkles or "fullness". As shown in Figs. 3 and 4, the core A⁵ does not completely fill the tubular portion, in length or cross-section.

20 I claim as my invention:

1. A garment of the class specified having a neck-band comprising a fabric portion, and a non-tubular cylindrical core covered by said portion, said core consisting of soft, flexible rubber

of sufficient resistance and bulk to prevent kinking during use, and means for securing the ends of the neck-band.

2. A garment of the class specified having a neck-band comprising an elongated member of 80 soft, flexible rubber, having a rounded cross-sectional form and of sufficiently large diameter, bulk and stiffness to prevent formation of kinks in use.

3. A garment of the class specified having a 85 neck-band comprising an elongated, soft, flexible member of sufficient resiliency, stiffness and cross-sectional bulk to prevent the formation of a kink during the use of the garment, as and for the purpose described.

4. A garment of the class specified having a neck-band comprising a tubular fabric portion, and a cylindrical core loosely contained within said portion, said core consisting of soft, flexible material of sufficient stiffness and bulk to hold 95 the tubular portion distended against objectionable folds, and means for securing the ends of the neck-band.
